UNITED STATES PATENT OFFICE

119,033

DESIGN FOR A FUSEE DISPENSER

Clark M. Bolser, Cedar Falls, Iowa

Application November 15, 1939, Serial No. 88,306

Term of patent 7 years

To all whom it may concern:

Be it known that I, Clark M. Bolser, a citizen of the United States and a resident of Cedar Falls, in the county of Blackhawk and State of Iowa, have invented a new, original, and ornamental Design for a Fussee Dispenser, of which the following is a specification, reference being had to the accompanying drawing forming part thereof.

Figure 1 is a perspective view of a fussee dispenser showing my new design;

Figure 2 is a plan view thereof;

Figure 3 is a front elevational view thereof;

and

Figure 4 is a side elevation of the right hand side of Figure 3 broken for convenience of illustration.

I claim:

The ornamental design for a fussee dispenser, substantially as shown.

CLARK M. BOLSER.
